UNITED STATES PATENT OFFICE.

CHARLES A. GREENE, OF STOCKTON, CALIFORNIA, ASSIGNOR OF ONE-HALF
TO WALTER E. BIDWELL, OF SAME PLACE.

MOWING-MACHINE.

SPECIFICATION forming part of Letters Patent No. 373,524, dated November 22, 1887.

Application filed January 11, 1887. Serial No. 224,070. (No model.)

To all whom it may concern:

Be it known that I, CHARLES A. GREENE, a citizen of the United States, residing at Stockton, in the county of San Joaquin, State of California, have invented certain new and useful Improvements in Mowing - Machines, of which the following is a specification, reference being had therein to the accompanying drawings.

10 My invention relates to a grass-cutting machine, more particularly to that class termed "mowing-machines," and which are used exclusively for cutting grass in large quantities.

In the accompanying drawings, Figure 1 represents a plan of a mowing-machine containing my improvements. Fig. 2 is an elevation of a ball-joint device connecting the pitman to the cutter-bar. Fig. 3 is a section through line Z Z, Fig. 2. Fig. 4 is a section 20 of the cutter-bar and finger-bar through line X X, Fig. 1.

Referring to the drawings, A A represent the wheels of a mowing-machine, and B the supporting iron frame, of which C is the main 25 and driving axle, carrying the wheels A, and at a proper location a main or driving spur-wheel, D, which intermeshes with a clutch spur-pinion, E, upon a shaft, G, which pinion, by its clutch, engages with the clutch of a 30 bevel-gear, F, upon shaft G. The gear F intermeshes with a bevel-gear, H, upon the end of a crank-shaft, I, upon the forward end of which are two crank-balances at needful positions, having suitable pins for the 35 reception of the jaws of the pitman L, by which the upper cutter-bar, N, is driven, and of the pitman L', by which the lower cutter-bar, O, is driven.

M is the usual shoe at the connection of the 40 finger-bar to the frame.

The finger-bar is composed of three portions—viz., a thick upper plate, S, a middle thin plate, T, to separate the cutter-bar, and a bottom plate, S'. The guard-fingers P are secured beneath the bottom plate, S', and are provided with channels in front of the plate S', so that the cutter-bar O may slide therein. The bar of the upper cutter-bar, N, slides in front of the upper plate, S, and upon guides 45 t, attached to the front edge of the bar T, and

is prevented from springing upward by keepers R, secured by bolts R' to the finger-bar, which bolts also aid to secure the plates S S' together.

The two strips r r', (shown in Fig. 4,) lying 55 between the rear edges of the cutter-bars and the front edges of the parts S S' of the finger-bar, are designed to serve as wearing-plates for the rear edges of the cutter-bar, and are preferably made of hardened steel. 50

The cutters N' are slightly curved or depressed, in order to enable them to enter the lips of the guards P, parallel with and just above the cutters of the cutter-bar O, so that the cutter-bars will easily pass each other and 65 their faces impinge upon each other, as in a pair of scissors.

In light grass, when an ordinary speed of 70 the team will answer for cutting purposes, the upper cutter-bar may be removed and its pitman disconnected and the lower cutter-bar alone used.

The articulated connection of the cutter-bar and pitman is accomplished by the use of a ball, g, upon the end of the pitman, the pitman 75 making a curve at the point of connection with the ball. This ball g is encompassed by a socket in two sliding ways, a and b, which ways are provided with grooves which slide upon tongues on the inside of a suitably-constructed 80 head, V, of the cutter - bar. The way b impinges upon the threaded head of a turn-screw, c, which is controlled by a head outside of the cutter-bar head V, the screw c passing through a suitable hole for that purpose. Lock-nuts d 85 and e, respectively inside and outside of the head V, secure the position of the screw c in relation to the ways a and b.

Freedom to act at any position of the cutter-bar is afforded by the ball g, so that, no 90 matter what is the angle of the finger-bar, the cutter-bar will operate easily. The head V is secured to the cutter - bar in any desired method.

Having thus described my invention, what I 95 claim as new, and desire to secure by Letters Patent, is—

The combination, substantially as described, of the frame B and wheels A, the main shaft C, the driving gearing composed of the spur- 100

wheel D, the clutch spur-pinion E, the clutch bevel-gear F, the bevel-pinion H, the crank-shaft I, having two crank-balances, K and J, with pins thereon at its outer end in suitable 5 positions, the pitmen L and L', connecting the crank-balances J and K, respectively, to the upper and lower cutter-bars, N and O, the pitmen being each provided with ball g, engaging with a socket-connection composing the head of each cutter-bar, consisting of the head V, the sliding blocks a and b, having grooves receiving the tongues f, and the lock screw

and nut c d e, the finger-bar consisting of the sections S T S', the middle section, T, having the slides for the cutter-bar N, suitable guard-fingers, P, and the cutter-bars N and O, operating in said finger-bar, the former being provided with downwardly-curving cutters. 15

In testimony whereof I affix my signature in presence of two witnesses.

CHARLES A. GREENE.
